UNITED STATES PATENT OFFICE.

JOSEPH B. LA ROCK, OF BELLEVUE, KENTUCKY, ASSIGNOR TO N. DRUCKER AND COMPANY, OF CINCINNATI, OHIO, A PARTNERSHIP COMPOSED OF NATHAN DRUCKER AND MORRIS N. DRUCKER.

DESIGN FOR A TRUNK-PAD.

SPECIFICATION forming part of Design No. 36,300, dated April 28, 1903.

Application filed December 3, 1902. Serial No. 133,780. Term of patent 7 years.

To all whom it may concern:

Be it known that I, JOSEPH B. LA ROCK, a citizen of the United States of America, and a resident of Bellevue, county of Campbell, 5 State of Kentucky, have invented a certain new and ornamental Design for Trunk-Pads, of which the following is a specification.

The figure is a plan view of a trunk-pad embodying my invention.

10 The cover C of the pad has printed upon it a series of intersecting equally-spaced straight bands, one series c being parallel one to the other and the other series c' crossing the series c and being likewise parallel to each 15 other, thereby dividing the surface of the

cover into a number of similarly-shaped diamond figures c². At the points of intersection of the bands c with bands c' a tufting button D is placed. Within the center of each diamond is a fleur-de-lis E. The fleur-de-lis in each diamond is placed at right angles in each adjacent diamond. 20

What I claim is—

An ornamental design for a trunk-pad as herein shown and described.

JOSEPH B. LA ROCK.
